LIQUID DEODORANT APPLICATOR

Thomas A. Jenkins, Glenview, Ill., assignor to Owens-Illinois Glass Company, Toledo, Ohio, a corporation of Ohio

Application June 21, 1956, Serial No. 41,999

Term of patent 14 years

(Cl. D86—10)

Fig. 1.

Fig. 2.

Fig. 3.

Fig. 1 is a side elevational view of a liquid deodorant applicator showing my new design.

Fig. 2 is a bottom plan view.

Fig. 3 is a fragmentary sectional view taken along the line 3—3 of Fig. 2, such showing substantially a one-half section of the combined base and closure portion.

I claim:

The ornamental design for a liquid deodorant applicator, substantially as shown and described.
